LAMP

Paul Chilo, Chicago, Ill.

Application December 18, 1939, Serial No. 309,719

3 Claims. (Cl. 248—185)

My invention relates to electric lamps and in particular to table lamps of the type having switch operating means extending above the lamp shades for convenient operation of the lamp switches.

One of the objects of my invention is to provide an improved lamp of this type having a shade which may be rocked or tilted relative to the lamp base whereby light from the lamp may be directed sidewardly as desired.

It is a further object of my invention to provide an improved lamp of this type in which the switch operating means and the lamp bulb are tilted as the shade is tilted.

My invention preferably contemplates a supporting member or cap adapted to be carried by a lamp base, two hollow supporting arms extending upwardly from the cap, and a housing member for the lamp switch and socket and carrying the lamp shade swingably mounted between the arms at their upper ends, and it is an object of my invention to provide means for holding the housing member and arms together under spring pressure whereby the housing member is held frictionally fixed relative to the arms.

It is a further object of my invention to provide an improved lamp construction of this type which may be easily wired and in which the housing member is so mounted between the upstanding arms that upon swinging movement of the housing member the electric supply wires will not be cut, damaged or broken.

Another object of my invention is the provision of improved means for mounting the lamp socket in the housing means therefor and which is so arranged that the mounting of the socket is not affected by turning the lamp bulb in the socket, either to remove or replace it.

In the preferred construction, the lamp socket is secured in place by a shank carried by the housing member, and it is another object of my invention to provide improved switch operating means extending through the shank and so arranged that the switch may be conveniently operated from a point above the shade regardless of the angle at which the shade may be tilted.

It is another object of my invention to provide an improved lamp construction of this type in which the upstanding arms are provided with tongues on their ends for attachment to the cap and housing members and in which the arms are of such construction that they may be manufactured easily and inexpensively.

It is still another object of my invention to

provide a lamp construction of this type in which improved means for removably fastening the cap to the lamp base are provided.

The invention consists of the novel constructions, arrangements and devices to be hereinafter described and claimed for carrying out the above stated objects and such other objects as will appear from the following description of a preferred embodiment of the invention illustrated in the accompanying drawings, wherein:

Fig. 1 is an elevational view of a lamp embodying the principles of my invention;

Fig. 2 is an elevational view similar to Fig. 1 and on an enlarged scale with the shade and certain other parts cut away for clearness of illustration;

Fig. 3 is an elevational view on an enlarged scale with certain of the parts cut away taken on line 3—3 of Fig. 1;

Fig. 4 is a plan view of the switch and socket housing member and adjacent parts taken on line 4—4 of Fig. 3;

Fig. 5 is a cross sectional view of the housing member taken on line 5—5 of Fig. 3;

Fig. 6 is a cross sectional view of the supporting arms taken on line 6—6 of Fig. 3;

Fig. 7 is a cross sectional view on an enlarged scale of the cap and associated parts taken on line 7—7 of Fig. 3;

Fig. 8 is a cross sectional view on an enlarged scale of the housing member taken on line 8—8 of Fig. 3 with the switch and socket unit removed for clearness of illustration;

Fig. 9 is a cross sectional view of a bearing plate cap; and

Fig. 10 is a plan view of a supporting arm in its initial state.

Like characters of reference designate like parts in the several views.

Referring to Fig. 1, the lamp 15 comprises in general a lamp base or pedestal 16, a shade support 17 and a shade 18. The lamp base may be of earthenware or any other suitable material. On its upper end the lamp base is provided with a central opening 19 and an outer groove 20 as is shown in Fig. 2.

The shade support 17 includes a cap or supporting member 21, the edges of which fit into the groove 20 as shown in Figs. 2 and 3. The cap is provided with obliquely extending sides 22, having openings 23 therein, and with a central opening 24 in its top.

As shown in Figs. 2, 3 and 7, a base member 25 having upwardly extending sides 26 is provided in the cap 21. A bridging member 27 is

welded to the member 25 at points 25a and has a central threaded opening 28 therein. The member 25 is provided with a central threaded opening 29 in which is positioned a hollow shank 30 which extends through the opening 19 in the lamp base 16. Inwardly extending lugs 31 are provided on the member 27 and these act to limit the upward movement of the shank 30 in the opening 29. A screw 32 passes through the opening 24 in the cap 21 and is screwed into the threaded opening 28 of the member 27 for holding the members 25 and 27 removably in the cap. In such position of the members 25 and 27 the outer arms 26 may bear against the oblique sides of the cap and the members 25 and 27 are thus limited in upward movement and are held against rotation in the cap by such engagement. A nut 33 is positioned on the shank 30 and bears against the under side of the lamp base 16 and holds the cap 21 tightly on the lamp base with its edges in the groove 20.

As best shown in Figs. 3 and 6, arms 34 extend through the openings 23 of the cap and are fastened to the cap by means of tongues 35 which are provided on the lower ends of the arms and are welded to the cap. Bearing plate members 36 in the form of cups are welded to tongues 37 which are provided on the upper ends of the arms 34. Each of the arms 34 is initially in the form of a narrow strip of metal 38, as shown in Fig. 10, having the spaced tongue portions 37 on its upper end and the centrally located tongue 35 on its lower end. The arms are formed by bending or rolling the strips of metal 38 into tubular form thereby bringing the tongue portions 37 together. The arms are also bent into curved form as shown in Fig. 3, thereby forming in effect, with the cap 21, a harp frame.

Caps 39, provided with slot-like openings 40 in their sides as shown in Fig. 9, fit into the members 36 as shown in Figs. 3 and 5. The openings 40 fit around the upper ends of the arms 34 and the caps 39 are removably held in the members 36 by frictional engagement therewith.

A housing member 41 is swingingly mounted between the bearing plate members 36 by means of tubular shafts 42 extending through the bearing plate members and into the housing member. Leaf springs 43 are provided on the shafts 42 bearing against the inside faces of the housing member 41 and against the inside hubs 42a of the shafts. The leaf springs 43 act to pull the shafts 42 inwardly with the outside hubs 42b of the shafts bearing against the members 36 and cause the housing member and bearing plate members to bear against each other under spring pressure. The housing member 41 is thereby held fixed relative to the bearing plate members 36 and the arms 34 by the frictional engagement between the bearing plate members and the housing member.

The bearing plate members 36 are provided with slots 44 as best shown in Fig. 2. The housing member 41 is provided with lugs 45 which extend into the respective slots. The lugs move in the slots with the swinging movement of the housing member and cooperate with the slots to limit the swinging movement of the housing member.

A complementary housing member 46 is provided and fits into the housing member 41 as shown best in Figs. 3 and 8. The housing member 46 is provided with a central opening 47 and

with an outwardly extending rib 48. The housing member 46 is limited in its upward movement by the rib 48 bearing against the lower edge of the housing member 41. The housing member 46 is provided with outwardly extending lugs 49 which fit into openings 50 in the housing member 41 and the housing member 46 is thereby held against downward movement out of the housing member 41. The arrangement is such that when the housing member 46 is inserted into the housing member 41, the lugs 49 are forced inwardly against their spring action by the housing member 41 until the rib 48 comes in contact with the lower edges of the housing member 41 whereupon the lugs 49 spring outwardly into the openings 50. The housing member 46 may be removed from the housing member 41 by forcing the lugs 49 inwardly such that they will pass the lower edge of the member 41 and then drawing the member 46 downwardly.

A switch and socket unit 51 provided in the housing member 41 extends through the opening 47 in the complementary housing member 46 and is held by the member 46 against sideward movement in the housing member 41. A lamp bulb 52 is positioned in the switch and socket unit 51, and the lamp arrangement is such that the bulb is located between the arms 34. The switch and socket unit is provided with a threaded shank 53 which extends through an opening 54 in the top of the housing member 41. As shown in Fig. 4 the shank 53 and the opening 54 have flat sides and are non-circular in form. The arrangement is such that when the lamp bulb 52 is removed or replaced in the switch and socket unit, the unit cannot have rotative movement relative to the member 41.

A lock nut 55 is positioned on the shank 53 and holds the switch and socket unit 51 from downward movement in the housing member 41. A shade carrying collar 56 from which shade carrying arms 57 extend is positioned on the lock nut 55 and is held in such position by a lock nut 58 on the shank 53. A shaft 59 extends through the shank 53 as shown in Fig. 2 and is connected with the switch and socket unit 51. A circuit through the switch in the unit 51 is completed and broken upon rotation of the shaft 59. A finial or switch knob 60 is positioned on the upper end of the shaft 59 and forms a switch operating means for rotating the shaft 59.

Electrical supply wires 61 extend upwardly from the base through the shank 30, into the arms 34 and through the hollow shaft 42 to the switch and socket unit in the housing member 41, as is shown in Fig. 3. The lamp arrangement is such that the wiring may be easily installed. With the members 25, 27, and the shank 30 free of the cap 21 and free of the base 16, the caps 39 removed from the members 36 and the switch and socket unit and complementary housing member 46 free of the housing member 41, wires 61 which have been preliminarily separated may be passed through the shank 30 and out on opposite sides of the member 27 to the arms 34. The wires may then be pushed through the arms, passed through the shafts 42, and connected to the switch and socket unit. The lamp arrangement may then be put into finished condition with the caps 39, the complementary housing member 46 and the switch and socket unit in place and with the lamp support 17 mounted on the base 16, as is apparent.

The finial or switch knob 60 extends above the shade 18 and the shade supporting means, in-

cluding the arms 57, as well as above the housing 41, and the lamp may be switched on or off very conveniently without reaching under the shade and feeling for the switch as is usually done. When it is desired to tilt the lamp shade 18, the lamp bulb 52 and associated parts, it is simply necessary to grasp any of the movable parts and swing the housing member 41 relative to the arms 34. The housing member 41 remains in a fixed position upon being tilted due to the action of the leaf springs 43. The arms 34 which are provided with tongues 35 and 37 for fastening the arms to the cap 21 and the bearing plates 36 are easily and inexpensively constructed. Electrical supply wiring is easily installed in my improved lamp arrangement as hereinbefore described. The members 25 and 27 in the cap 21 form suitable and satisfactory means for removably fastening the shade support 17 to the lamp base 16. The wiring, the upper ends of the arms 34, and the slot and lug arrangement are all hidden by the removable caps 39, and there is no detraction from the finished appearance of the lamp arrangement by these parts. The slot 44 and lug 45 cooperate to limit the swinging movement of the housing member 41, and the wires 61 cannot therefore be broken or damaged by too great a swinging movement of the housing member.

I do not intend to limit the invention to the details of construction shown and described except only in so far as certain of the appended claims are specifically so limited, as it will be obvious that modifications may be made without departing from the principles of the invention.

I claim:

1. In a support for lamps, the combination of a pedestal having a supporting area on its upper end, a base member on said supporting area, an inverted U-shaped bridging member secured at its ends to said base member, a cap member fitting over said bridging member and around said base member, means for securing the cap to said bridge member, and means for securing the base member to said pedestal.
2. In a support for lamps, the combination of a pedestal having a supporting area on its upper end, a base member on said supporting area and having upstanding marginal portions, an inverted U-shaped bridging member secured at its ends to said base member, a cap member fitting over said bridging member and having its sides extending downwardly and surrounding said marginal portions, means for securing the cap to said bridge member, and means for securing the base member to said pedestal.
3. In a support for lamps, the combination of a pedestal having a supporting area on its upper end, base means on said supporting area, a cap member comprising a vertical wall portion and a flange portion angularly disposed relative thereto, said cap member fitting over and around said base means, means for securing said base means to said pedestal, means for securing said cap member to said base means, and a supporting arm having one end extending through an opening in the flange portion of the cap member and secured to the inner side of the vertical wall portion of the cap member, said secured portion of the arm coacting with said base means for limiting rotative movement of the cap member and arm with respect to the base means.

PAUL CHILO.
